UNITED STATES PATENT OFFICE.

GEORGE W. ARNOLD, OF DENVER, COLORADO, ASSIGNOR OF ONE-THIRD TO HARRY HERTZBERG, OF DENVER, COLORADO.

ORE-CONCENTRATING MACHINE.

1,081,421.

Specification of Letters Patent. Patented Dec. 16, 1913.

Application filed June 26, 1913. Serial No. 775,920.

To all whom it may concern:

Be it known that I, GEORGE W. ARNOLD, a citizen of the United States, residing in the city and county of Denver and State of Colorado, have invented certain new and useful Improvements in Ore-Concentrating Machines; and I do hereby declare the following to be a full, clear, and exact description of the invention, such as will enable others skilled in the art to which it appertains to make and use the same.

This invention relates to ore concentrating machines for wet and dry concentrating, and has for its object the separation of the values or concentrated mineral from the gangue or waste, by a rotating adjustably inclined dish or pan with involute riffles or grooves on the inside bottom of the pan, the material to be treated, being thrown into the pan at the periphery, and the pan discharging the values or concentrate through a central outlet, and the gangue over the rim or flange of the pan.

This invention contemplates and embodies a structural feature, for the above purpose, which is simple and inexpensive in first cost and maintenance; which may be freely manipulated by hand where water or power is not available, and is very efficient in its operation where water and power is available; the inclination of the pan being adjustable to suit the different grades or character of material, to be concentrated wet or dry.

The object of this invention is to avoid the difficulty experienced in concentrating ore by centrifugal, vibrating or oscillating means, as a great deal of the values are lost, and the maintenance is very costly.

A further object of the invention is to produce a hand-operated ore concentrating machine, light in weight, that may be moved from place to place, so that it may be used for dry placer mining, in deserts where there is no water, but an abundance of placer sand, as this invention is very rapid for large outputs of concentrate with the dry or wet methods.

In carrying out my invention I employ the novel construction hereinafter fully described and claimed.

In the drawings accompanying this specification, like parts in the several views, have been given the same reference numbers.

Figure 1 is a side elevation of machine

in operation. Fig. 2 is a front view of the same. Fig. 3 is a sectional view of a square riffle. Fig. 4 is a sectional view of a narrow V riffle. Fig. 5 is a sectional view of a wide V riffle. Fig. 6 is a sectional view of a round groove riffle. Fig. 7 is a sectional view of an L channel riffle. Fig. 8 is a sectional view of the pan and hollow shaft, showing the riffles diminishing in height, as they approach the central hollow shaft. Fig. 9 is a sectional view of a square groove. Fig. 10 is a sectional view of a narrow V groove. Fig. 11 is a sectional view of a wide V groove. Fig. 12 is a sectional view of a round groove. Fig. 13 is a sectional view of an L groove. Fig. 14 is a sectional view of the pan showing the grooves diminishing in depth as they approach the central hollow shaft.

The pan 1 is substantially secured to the hollow shaft 2, and has at its periphery, the rim 3, with the square involute riffles 4, secured to the inside bottom of the pan; the outer ends of the riffles are in contact with the rim 3, and the inner ends of the riffles terminate at the central opening in the shaft. For concentrating ore of different grades and character, I use the different kinds of riffles as shown, in Fig. 3 the square riffle 4, in Fig. 4 the narrow V riffle 4', in Fig. 5, the wide V riffle 4'', in Fig. 6, the round groove riffle 4'', in Fig. 7, the L channel riffle 4'', all the riffles diminish in height as they approach the central opening of the pan as shown in Fig. 8. I also use grooves which are cut into the pan as shown, in Fig. 9, as the square groove 5, in Fig. 10, as the narrow V groove 5', in Fig. 11, as the wide V groove 5'', in Fig. 12, as the round groove 5'', in Fig. 13, as the L groove 5'', all the grooves diminish in depth as they approach the central hollow shaft. The concentrates or values 18 to 18" respectively are shown in the different riffles and grooves in their relative positions when machine is in operation.

The pan is rotated upon its central hollow shaft, in the adjustably inclined bearing 6, which is locked in the desired angular position by the clamp 7, to the supporting base 8. Rotary motion is imparted to the pan; by revolving the pulley 9, by a belt from any suitable source of energy, or by means of the handle 10.

The material is fed into the pan by any

suitable means at the lower left hand part of the pan, the concentrates or values fall through the central hollow shaft into the value can 15, and the gangue 12 leaves the 5 pan over the rim at the lower right hand part of the pan. When using this machine for wet concentration the dressing water is applied by means of the spray pipe 14.

In using this machine the material is 10 thrown into the slowly revolving inclined 15 pan, at the lower left hand part of the pan, the rim prevents this material from falling out and acts as a conveyer to carry the material over to the lower right hand part 20 of the pan where the rotary motion causes this material to tumble over and over, which causes the heavy particles to precipitate to the bottom angle, formed by the bottom of pan and its rim, where it is taken up by the 25 riffles or grooves and carried upward a short distance above the horizontal center. There it starts to roll and tumble down the side of the riffles, the difference in specific 30 gravities causes the heavy values to precipitate, the light gangue rises to the surface of the riffles, and as it moves toward the center on the riffles and as the riffles diminish in height, the gangue rolls over the riffles as its supporting ledge is reduced 35 to carry the values only, to the hole in the central shaft, where it falls into the values can. The gangue falls and tumbles to the lower right hand part of pan on the rim, until there accumulates a larger amount 40 than the rim can carry, then the surplus rolls over the rim as gangue, free from any values. This rim or flange is a very important part of this invention as it takes care of the material that is fed into the pan, it 45 feeds the riffles or grooves, it produces quick precipitation; and discharges the gangue, and I vary its angular position in relation to the pan for different ores. It is not to be understood, however, that the invention 50 is limited in this respect, to any particular material or form, as shown and described as it will be evident that many changes may be made, in the details, of construction, shown and described without departing from the scope of the invention.

Having thus described my invention, what I claim and desire to protect by Letters Patent of the United States is—

1. In an ore concentrator, a rotating ad-

justably inclined flat pan, with a rim at 55 right angles to the surface of the pan, a central hollow shaft, involute riffles secured to said pan and a base supporting said pan, with adjustable means secured to said base for adjusting the angle of inclination of said pan.

2. In an ore concentrator, a rotating adjustably inclined flat pan, with a rim at 60 right angles to the surface of the pan, a central hollow shaft, involute riffles secured to said pan, extending from said rim to said hollow shaft and means on the hollow shaft for rotating the pan.

3. In an ore concentrator, a rotating adjustably inclined flat pan, with a rim at 70 right angles to the surface of the pan, a central hollow shaft, riffles secured to said pan extending from the rim to the central hollow shaft, said riffles diminishing in height as they approach the central hollow 75 shaft.

4. In an ore concentrator, a rotating adjustably inclined flat pan with a rim at 80 right angles to the surface of the pan, a central hollow shaft, riffles secured to said pan extending from the rim to the central hollow shaft, said riffles being involute and diminishing in height as they approach the central hollow shaft.

5. In an ore concentrator, a rotating ad- 85 justably inclined flat pan with a rim at right angles to the surface of the pan, a central hollow shaft, riffles secured to said pan extending from the rim to the central hollow shaft, square involute riffles diminishing 90 in height as they approach the central hollow shaft.

6. In an ore concentrator, a rotating adjustably inclined flat pan, with a rim at 95 right angles to the surface of the pan, a central hollow shaft, riffles secured to said pan, extending from the rim to the central hollow shaft, said riffles being involute and diminishing in height as they approach the central hollow shaft, said rim being in contact with the outer ends of the riffles, forming wide angles between said rim and said riffles.

GEORGE W. ARNOLD.
